UNITED STATES PATENT OFFICE.

PRYOR L. MILLER, OF PLANT CITY, FLORIDA.

DESIGN FOR A SERVICE-FLAG.

57,192.

Specification for Design.

Patented Mar. 1, 1921.

Application filed October 11, 1918. Serial No. 257,801. Term of patent 3½ years.

To all whom it may concern:

Be it known that I, PRYOR L. MILLER, a citizen of the United States, residing at Plant City, in the county of Hillsborough and State of Florida, have invented a new, original, and ornamental Design for a Service-Flag, of which the following is a specification, reference being had to the accompanying drawing, forming part thereof.

The figure is a plan view of the flag showing my new design.

I claim:

The ornamental design for a service flag, as shown.

PRYOR L. MILLER.
